DESIGN FOR AN AMUSEMENT APPARATUS

John H. C. Motley and Henry J. G. Walter,
Chicago, Ill.

Application September 4, 1945, Serial No. 121,826

Term of patent 14 years

(Cl. D34—5)

To all whom it may concern:

Be it known that we, John H. C. Motley and Henry J. G. Walter, citizens of the United States, residing at Chicago, in the county of Cook and State of Illinois, have invented a new, original, and ornamental Design for an Amusement Apparatus, of which the following is a specification, reference being made to the accompanying drawing, forming a part thereof.

In the drawing:

Fig. 1 is a perspective view of an amusement apparatus showing our new design; and

Fig. 2 is a fragmental sectional view taken substantially along the line 2—2 of Fig. 1.

We claim:

The ornamental design for an amusement apparatus, substantially as shown.

JOHN H. C. MOTLEY.
HENRY J. G. WALTER.
